[57] **CLAIM**

The ornamental design for a aquatic vessel connector with suction cups, as shown and described.

DESCRIPTION

FIG. 1 is a front elevational view of the aquatic vessel connector with suction cups according to my design. The broken lines showing two boats are for environmental purposes only and form no part of the claimed design;

FIG. 2 is a rear perspective view of the aquatic vessel connector with suction cups;

FIG. 3 is a front perspective view of the aquatic vessel connector with suction cups;

FIG. 4 is a front perspective view of an alternate design of my aquatic vessel connector with suction cups; and, FIG. 5 is a rear perspective view of the alternate design of my aquatic vessel connector with suction cups.

FIG. 1

FIG. 3

FIG. 2
